AERIAL APPARATUS

Eugene Weissman, Baltimore, Md.

Application April 8, 1944, Serial No. 530,216

6 Claims. (Cl. 244—138)

This invention relates to improvements in air floats, and more particularly to a novel device adapted to be propelled into the atmosphere or released from an aircraft and which will be retarded in its descent.

One of the objects of the invention is to provide a novel device of this character which may be used as an airmail pick-up, aerial barrage bomb, distress signal, either pyrotechnic or electric, aerial smoke screen, aerial fence support, or the like.

Another object is to provide an aerial float having blades especially shaped to compel the float to travel extremely slowly downwardly due to gravity.

With the foregoing objects outlined, and with other objects in view which will appear as the description proceeds, the invention consists in the novel features hereinafter described in detail, illustrated in the accompanying drawing, and more particularly pointed out in the appended claims.

In the drawing—

Fig. 1 is a side elevation of my aerial apparatus with the blades in retracted position.

Fig. 2 is a sectional view on the line 2—2 of Fig. 1.

Fig. 3 is a similar view on the line 3—3 of Fig. 1.

Fig. 4 is a fragmentary vertical sectional view taken on the line 4—4 of Fig. 1.

Fig. 5 is a top plan view of one of the vanes or blades.

Figs. 6, 7, 8, 9, 10, 11, and 12 are sectional views of one of the blades taken respectively on the lines 6—6, 7—7, 8—8, 9—9, 10—10, 11—11, and 12—12 of Fig. 5.

Referring to the drawing, 13 designates a hollow capsule of streamline shape to facilitate its travel through the atmosphere and provided with a pointed nose 14 to aid in its speedy flight in the event it is propelled upwardly into the air from a catapult or the like. At the base of the nose, the capsule is provided with recesses 15 to receive the root ends 16 of blades 17. Each blade is hingedly connected near its root end to the capsule, as indicated at 18, for swinging movement about a horizontal axis, and at the bottom of the recesses there is a shelf 19 on which the root ends of the blades can come to rest when the blades are in a horizontal position to prevent them from rising beyond such a position.

In accordance with the invention the blade when in horizontal position has at its root end substantially parallel plane top and bottom surfaces 20 and 21 arranged in a substantially hori-

zontal plane, and the bottom surface 21 continues in a horizontal plane to a point 22 adjacent to the tip 23 of the blade.

The trailing edge portion 24 of each blade 5 gradually increases in thickness from the root of the blade toward the point 22, and the upper surface 20 inclines gradually upward from the leading edge 25 to the trailing edge, as indicated in Figs. 7 to 10, inclusive. Such inclined surfaces continue on to the tip portion 26 of the blade as indicated in Figs. 11 and 12, and it will be noted in these figures that the undersurface of this portion is, also, gradually inclined upward from the leading edge to the trailing edge.

15 At a portion of the blade intermediate its ends and near the point 22 where the thickness is absent, the blade is provided at its under side with a longitudinal recess 27 at its leading edge and a similar recess 28 at its trailing edge.

10 As shown in Fig. 5, the opposite edges of the blade are substantially parallel from its root to its tip portion 26, and the edges of the latter are curved as indicated at 29 and 30; the edge 30 being bowed rearwardly and both of these edges have portions converging toward the extremity 23.

25 The device was primarily designed and tested for airmail pick-up and in such tests the capsule was discharged into the air as high as possible by catapult or other means so that it could be picked-up by aircraft in its air floating stage. As soon as it reached its greatest height and started to descend, the blades automatically moved from a vertical position into a horizontal position, indicated in Fig. 3, and then as the whole device 30 revolved about a vertical axis, the blades tended to keep the capsule afloat for considerable periods of time.

35 Obviously if the capsule is hollow, it can be employed for the storage of airmail, to carry a bomb, signals of various types, smoke-producing materials, and the like, and owing to the shapes of the blades, a considerable period of time will be taken up in its descent, so it will admirably serve for such purposes.

40 45 While I have disclosed what I now consider to be a preferred embodiment of my invention in such manner that it will be readily understood by those skilled in the art, I am aware changes may be made in the details disclosed without departing from the spirit of the invention, as expressed in the following claims.

What I claim and desire to secure by Letters Patent is:

50 55 1. An aerial apparatus comprising a hollow vertically projectible capsule including a solid

pointed nose portion, a series of substantially flat blades surrounding the capsule and hingedly connected near their root ends to the base of the nose portion for movement into a substantially horizontal plane upon downward gravitational movement of the capsule, each blade consisting of a body portion and a tip portion, the opposite side surfaces of the body portion converging toward the leading edge of the blade substantially throughout the length of the body, and the trailing edge portion of the body of the blade gradually increasing in thickness from the root toward the tip portion of the blade.

2. An aerial apparatus comprising a hollow vertical projectible capsule including a solid pointed nose portion, a series of substantially flat blades surrounding the capsule and hingedly connected near their root ends to the base of the nose portion for movement into a substantially horizontal plane upon downward gravitational movement of the capsule, each blade consisting of a body portion and a tip portion, the opposite side surfaces of the body portion converging toward the leading edge of the blade substantially throughout the length of the body, and the trailing edge portion of the body of the blade gradually increasing in thickness from the root toward the tip portion of the blade, the leading and trailing edges of the body portion of the blade being provided with longitudinally extending recesses adjacent to the tip portion of the blade.

3. An aerial apparatus comprising a hollow vertically projectible capsule, including a solid pointed nose portion, a series of substantially flat blades surrounding the capsule and hingedly connected near their root ends to the base of the nose portion for movement into a substantially horizontal plane upon downward gravitational movement of the capsule, each blade consisting of a body portion and a tip portion, the opposite side surfaces of the body portion converging toward the leading edge of the blade substantially throughout the length of the body, and the trailing edge portion of the body of the blade gradually increasing in thickness from the root toward the tip portion of the blade, the tip portion of the blade having substantially parallel opposite surfaces inclined upwardly from the leading edge to the trailing edge of said tip portion.

4. An aerial apparatus comprising a hollow vertically projectible capsule including a solid pointed nose portion, a series of substantially

flat blades surrounding the capsule and hingedly connected near their root ends to the base of the nose portion for movement into a substantially horizontal plane upon downward gravitational movement of the capsule, each blade consisting of a body portion and a tip portion, the opposite side surfaces of the body portion converging toward the leading edge of the blade substantially throughout the length of the body, and the trailing edge portion of the body of the blade gradually increasing in thickness from the root toward the tip portion of the blade, the leading and trailing edges of the tip portion being curved and converging toward the tip of the blade.

5. An aerial apparatus comprising a hollow vertically projectible capsule including a solid pointed nose portion, a series of substantially flat blades surrounding the capsule and hingedly connected near their root ends to the base of the nose portion for movement into a substantially horizontal plane upon downward gravitational movement of the capsule, each blade consisting of a body portion and a tip portion, the body portion having substantially parallel leading and trailing edges, the opposite side surfaces of the body portion converging toward the leading edge of the blade substantially throughout the length of the body and the trailing edge portion of the body of the blade gradually increasing in thickness from the root toward the tip portion of the blade.

6. An aerial apparatus comprising a hollow vertically projectible capsule including a solid pointed nose portion, a series of substantially flat blades surrounding the capsule and hingedly connected near their root ends to the base of the nose portion for movement into a substantially horizontal plane upon downward gravitational movement of the capsule, each blade consisting of a body portion and a tip portion, the opposite side surfaces of the body portion converging toward the leading edge of the blade substantially throughout the length of the body, and the trailing edge portion of the body of the blade gradually increasing in thickness from the root toward the tip portion of the blade, the tip portion of the blade being wider than the body portion and the trailing edge of the tip portion being bowed rearwardly from the tip of the blade to a point adjacent to the outer end of the body portion.
